J. F. MENNINGEN.
FLUID PRESSURE GOVERNOR.
APPLICATION FILED MAY 20, 1909.

1,048,424.

Patented Dec. 24, 1912.

Fig. 2.

UNITED STATES PATENT OFFICE.

JOSEPH F. MENNINGEN, OF WEST ALLIS, WISCONSIN, ASSIGNEE TO ALLIS-CHALMERS COMPANY, A CORPORATION OF NEW JERSEY.

FLUID-PRESSURE GOVERNOR.

1,048,424.

Specification of Letters Patent. Patented Dec. 24, 1912.

Application filed May 20, 1909. Serial No. 497,321.

To all whom it may concern:

Be it known that I, JOSEPH F. MENNINGEN, a citizen of the United States, residing at West Allis, in the county of Milwaukee and State of Wisconsin, have invented certain new and useful Improvements in Fluid-Pressure Governors, of which the following is a full, clear, and exact specification.

This invention relates to governors for fluid pressure systems and particularly to that type of governor which includes an electric switch together with suitable means for operating the switch so as to close or open the circuit of an electric motor which drives a compressor when the fluid pressure varies beyond certain predetermined limits.

The object of my invention is to improve the operation of fluid pressure governors, and more specifically to provide a quick make and break switch to avoid excessive and destructive arcing.

The invention consists in certain novel details of construction and combinations and arrangements of parts which will be described in the specification and set forth in the accompanying claims.

Reference is had to the accompanying sheet of drawings, in which—

Figure 1 is a sectional view taken through a governor constructed in accordance with my invention, parts being broken away for the sake of clearness and the switch being here shown open; Fig. 2 is a sectional view taken through the line 2—2 of Fig. 1; Fig. 3 is a perspective view of the tripping mechanism employed in the operation of the governor; Figs. 4 and 5 are partial sectional views of the tripping mechanism, the latter view showing one element in an intermediate position while moving from one extreme position to another.

Referring to the figures of the drawing, 10 represents a casting which includes a cylinder or casing 11, and a flat base 11^a at one end of the cylinder for supporting part of the governor mechanism. At the opposite end of the cylinder is a tightly clamped flexible diaphragm 12 which is preferably made of strong rubber and is adapted to be shifted back and forth by variations in fluid pressure so as to operate the governor, the diaphragm being clamped between the open end of the cylinder and a cap 13 which is secured to the cylinder. Between one side of the diaphragm and cap is a cavity or cham-

ber 14 which will be connected to the fluid reservoir or to the pressure system by a pipe (not shown) adapted to be screwed into sockets 15. On the opposite side of the diaphragm and engaging the latter so as to be shifted inward and outward by variations in the flexure thereof, is a head or enlarged portion 16 of the plunger having a shank 17 which extends through the cylinder and has its free end extending through an opening in the base 11^a. Movement of the plunger and of the diaphragm 12 is resisted by a rather heavy coil spring 18 which surrounds the shank 17 of the plunger and bears against the enlarged portion 16 thereof and a disk 19 which may be adjusted by set screws 20 extending through the base 11^a of the casting and engaging the disk 19. By adjusting these screws in the well known manner, the high and low limits of fluid pressure may be varied. The outer end of the plunger 17 is provided with a reduced portion 21 and with a pair of shoulders or flanges 22 and 23 between which the end of a lever, to be referred to presently, is held, and the latter of which serves, by engagement with a block 23^a secured to the top of the base, to limit the inward movement of the plunger.

The switch operating mechanism of the governor is supported by a frame 24 which is secured to the base 11^a by means of screws. Mounted on said frame and secured thereto is a casing inclosing two cylinders 25 and 26. A rod or follower 27, which is flattened and slotted near one end as shown in Fig. 3, having a sliding fit, operates in one of the cylinders 25. The other cylinder 26 is provided with two chambers 28 and 29 which terminate in ports 41 and 42 respectively which are connected alternately with an exhaust port 148 through an intermediate air passageway. The cylinder is further provided with a piston 30, working in the first mentioned chamber 28, and another piston 31 working in the second chamber 29. These pistons are provided with packing 30^a and 31^a at their ends, as shown in Fig. 2, to make an air tight fit in the chambers. Both pistons have reduced threaded portions 33 and 33^a respectively and operate from a central position. The pistons 30 and 31 are parallel to the follower 27 and are mechanically fastened to it by means of end plates 34 and 35, the former serving as a contact support

for the contact finger 36. A valve 37 comprising a casing 38 inside of which is an air chamber 39 and slide 40 having an air passageway 43 registering in turn with the three ports 41, 42, and 48, is connected to the cylinder 26. This valve will be connected to the fluid reservoir by a pipe 37. A pin 44 having an enlarged portion 45 and a reduced portion 46 extends through one side of the casing 38 of the valve 37 and makes a snug fit therewith. The enlarged portion 45 bears firmly against the casing, thus preventing an escape of the fluid due to a leak. The reduced portion 46 of the pin which is eccentric to the enlarged portion of the pin engages a vertical groove 40 in the slide 40, the latter being made to move in a reciprocating motion by the action of a crank 47 which is fastened to the outer end of the pin 44. This crank is given its motion from the action of the lever 48 through a rod or member 49 which is pivotally connected to said eccentric at 50 and to said lever at 51. Another rod or member 52 which is provided with slots 53 is pivotally connected at 54 to the outer end of the lever 48. The two rods 27 and 52 form the follower and tripping mechanism of the switch, the operation of which will be presently explained. An insulating block 55 carrying a contact segment 56 is mounted on the casing inclosing the cylinders 25 and 26. Secured to either side of said block 55 and insulated from the contact segment 56 are the poles 57 of a blow-out magnet. Located between these poles and supported thereby at one extremity is the magnet core 58 which is provided with a coil wrapped on a spool 59. The blow-out magnet is connected in series with the motor circuit which includes the switch, and the poles are located so that the path of the flux includes the point at which the circuit is made and broken. In this way arcing is reduced to a minimum.

The governor, which may be located in any desired position relative to the compressor will be adjusted by means of screws 20 so as to operate at a desired maximum or minimum pressure which may be varied between any desired points, say for example, between 90 pounds and 100 pounds. The range of pressure or the difference between the maximum and minimum pressures may be varied by varying the distance between the slots 53 in the rod 52. Assuming that the switch is open and the motor which drives the compressor is stationary, the plunger will move gradually inward, relative to the cylinder 60 as the fluid pressure is decreased and as the diaphragm becomes less flexed. As the plunger moves inward the members 49 and 52 are gradually moved outward, one of the members 52 sliding upward in a slot 60 in the follower 27 from the upper slot in said

member 52 to the lower slot. At the same time the member 49 connected to the crank 47 is operating the slide 40 in the valve 37 in such a manner as to allow the compressed fluid to be admitted into the chamber 29 through the port 42 and also permitting the fluid in chamber 28 to escape through port 41 through the intermediate air passageway 43 in the slide to the exhaust port 148. Just at the moment the lower slot in the member 52 reaches the flattened portion of the follower 27, the pressure under the diaphragm 12 has reached a minimum, the pressure on the piston 31 in cylinder 26 has reached a maximum, and the follower 27 and two pistons are forced to the right with a snap action by means of the fluid pressure, thus closing the electric circuit through the contact finger 36 and contact segment 56. The follower 27 is locked, thus preventing its movement, by means of the member 52 until the valve is wide open allowing the full pressure to be exerted on the piston 32. This arrangement has been provided in order to open and close the switch with a quick snap action. At the instant the electric circuit is closed, the motor is started and the compressed fluid is pumped through the reservoir into the cavity 14 under the diaphragm 12, thus compressing the spring 18 and moving the plunger and shank 17 outward relative to the cylinder. At the same time the members 49 and 52 are drawn inwardly, the former operating the slide and causing it to move to the right so as to allow the port 42 to register with the air passageway 43 in said slide and connect with the exhaust port 148, and the upper slot of the latter to gradually approach the flattened portion of the follower 27. When the upper slot in said member 52 has reached the flattened portion of follower 27 the pressure on the diaphragm and plunger has become a maximum as has the pressure on the piston 30 in cylinder 28, and the follower 27 and two pistons are thrown or shifted to the left with a snap action, breaking the electric circuit.

The mechanism which I have described above has proven by practice to be extremely efficient and reliable and in fact answers all the requirements of operation and practicability and at the same time is compact and inexpensive to manufacture.

I do not desire to be confined to the exact details shown and described, but aim in my claims to cover all modifications which do not involve a departure from the spirit and scope of my invention.

What I claim as new is:

1. In a governor for fluid pressure systems, a plunger responsive to variations in fluid pressure, a switch responsive to the action of said plunger, a follower connected to said switch, a notched movable member

through which the follower slides and for controlling the movement of said follower, and a valve for controlling the operation of said switch.

5. 2. In a governor for a fluid pressure system, a plunger responsive to variations in fluid pressure, a lever connected to said plunger, a member coöperating with said lever, a valve operated by said member, a slotted member also coöperating with said lever, a follower adapted to slide in and controlled by said slotted member, and a switch associated with the follower and which is opened and closed by a fluid under pressure.

15. 3. In a governor for a fluid pressure system, a plunger responsive to variations in fluid pressure, a lever connected to said plunger, a plurality of members coöperating with said lever, a valve responsive to the movements of said lever transmitted through one of said members, a follower and a piston the movements of both of which are controlled by another of said members.

25. 4. In a fluid pressure governor, a member responsive to variations in fluid pressure, a pivoted lever connected to said member, a rod provided with slots and coöperating with said lever, a switch responsive to motion transmitted through said member, lever, and rod, and a follower associated with said switch and held against movement during a certain range of fluid pressure by said rod.

35. 5. In a governor for a fluid pressure system, a plunger responsive to variations in fluid pressure, a lever connected to said plunger, a switch responsive to motion transmitted through said plunger and lever, a member coöperating with said lever, a valve adapted to regulate a flow of fluid for effecting the positions of said switch and operated by a movement of said member, a plurality of cylinders adjacent said switch, 45 a follower arranged to slide in one of said cylinders, and another member connected to said lever and arranged to trip said follower.

60. 6. In combination, in a governor for fluid pressure systems, a plunger responsive to variations in fluid pressure, a pivoted lever connected to said plunger, a switch responsive to motion transmitted through said plunger and lever, two members coöperating with said lever, two cylinders adjacent said switch, two pistons arranged to slide in one cylinder, a follower in the other said cylinder, said follower and said pistons connected to move simultaneously, a valve operated by one of said members to regulate the flow of fluid in one of said cylinders, the other said member for tripping said follower to permit the opening and closing of said switch.

65. 7. In combination, in a fluid pressure gov-

ernor, a plunger responsive to variations in fluid pressure, a lever connected to said plunger, a switch responsive to motion transmitted by said plunger through said lever, a follower provided with means for holding said follower against movement during a certain range of fluid pressure, said means comprising a slotted member coöperating with said lever, said lever coöperating with said plunger so that when the latter is moved a certain amount in one direction said follower is shifted from one position to another to permit the switch to be opened and when the plunger is moved a certain amount in the opposite direction said follower is shifted to another position to permit the switch to be closed.

8. In a governor for fluid pressure systems, a plunger responsive to variations in fluid pressure, a lever connected to said plunger, a plurality of members coöperating with said lever, a switch responsive to motion transmitted by said plunger through said lever and members, a valve operated by the action of one of said members, a cylinder adjacent said switch and containing a plurality of chambers, said valve to regulate the flow of fluid in said chambers, a follower operated by another said member, a piston arranged in said cylinder and mechanically fastened to said follower providing for the simultaneous movement of said piston and said follower.

9. In a governor for fluid pressure systems, a plunger responsive in more than one direction to variations in fluid pressure, a lever connected to said plunger, a switch controlled by the movement of said lever, and means for opening and closing an electric circuit comprising a valve, a piston, and a follower, the latter of which is mechanically connected to said piston to cause a simultaneous movement of said piston and follower when the electric circuit is opened or closed, the valve being movable over a plurality of ports under different operating conditions, and a plurality of members mounted on said lever one for operating said valve and another for tripping said follower.

10. In a governor for a fluid pressure system, a plunger responsive to variations in fluid pressure, a lever connected to said plunger, a plurality of members mounted on said lever, a valve adapted to be actuated over a plurality of ports under different operating conditions by one of said members, a follower coöperating with the other said member to trip said follower, and a piston permitted to move in more than one direction by the tripping of said follower.

11. In a fluid pressure governor, switch contacts, pneumatically operated means for moving said contacts into and out of engagement, a controlling valve, means com-

- prising a plurality of notched members each of which alternately moves in the notches of the other, and connections between said parts whereby the operation of said contact moving means is prevented until said valve is completely opened.
12. In combination, switch contacts, pneumatically operated means for moving one of said contacts into and out of engagement with another, a valve for controlling said pneumatically operated means, means for locking said movable contact in position when the contacts are in engagement and when they are out of engagement, means responsive to variations in fluid pressure, and means operated by said last mentioned means for controlling the operation of said valve and locking means.
13. In combination, switch contacts, pneu-

matically operated means for moving one 20 of said contacts into and out of engagement with another, a valve for controlling said pneumatically operated means, means for locking said movable contact in position when the contacts are in engagement and 25 when they are out of engagement, means responsive to variations in fluid pressure, and means operated by said last mentioned means for opening said valve and then releasing the movable contact from said locking means.

In testimony whereof I affix my signature, in the presence of two witnesses.

JOSEPH F. MENNINGEN.
